UNITED STATES PATENT OFFICE

HERBERT EDWARD PRICE, OF SEATTLE, WASHINGTON

ANIMATED TOY

Application filed January 29, 1927. Serial No. 164,561.

This invention relates to an animated toy, one of the objects being to provide a body simulating an animal containing a motor having means, actuated thereby whereby the 5 legs of the toy will be moved in properly timed relation, the legs being so jointed that, during such movement, a walking action will be produced and the toy move forward with a motion similar to that of the animal represented.

A further object is to provide supplemental mechanism likewise actuated by the motor whereby the head can be caused to swing from side to side, the eyes, ears and tongue 15 can be caused to move, the lower jaw will work relative to the other jaw, etc.

Another object is to provide a means for holding the mechanism against actuation, said means, when shifted from normal position, however, serving to release the motor so that the several parts will be actuated.

Another object is to provide power transmitting mechanism which is simple, compact and efficient and can be reached readily for 25 the purpose of making adjustments and repairs.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within 35 the scope of what is claimed, without departing from the spirit of the invention.

In the accompanying drawings, the preferred form of the invention has been shown.

In said drawings,

Figure 1 is a horizontal section through the body portion of the casing of the toy, the mechanism therein being shown in plan, the head portion of the casing being illustrated partly in plan and partly in section and the 45 outline of the covering of the toy being indicated by broken lines.

Figure 2 is a central vertical section through the head and body portion of the casing showing the operating mechanism in 50 elevation.

Figure 3 is a view similar to Figure 2 viewing the mechanism from the opposite side, the head portion of the casing being shown in elevation.

Figure 4 is a section on line 4—4, Figure 2. 55

Figure 5 is a detail view of the mechanism employed for actuating the lower jaw, tongue, eyes and ears.

Figure 6 is a view in diagram showing one position of the forward right leg of the toy 60 during the forward movement of the device.

Figure 7 is a similar view showing another position.

Figure 8 is a view like Figure 7 but showing a third position. 65

Figure 9 is a view illustrating a fourth position of the leg.

Referring to the figures by characters of reference 1 designates a casing formed of any suitable material simulating the body of an animal, this casing being provided on one side with a large opening 2 normally closed by a door 3 hingedly mounted and which, when closed, forms a portion of the surface of the body. The neck portion of the body 75 is open as shown at 4 and formed in the bottom portion of the body casing near the front and back ends thereof are openings 5 for the reception of the leg portions of the toy. 80

A main or base strip 6 is extended longitudinally within the body portion 1 and is fixedly secured in any suitable manner to said body portion. This strip extends between the front openings 5 and the rear openings 5 and has cross strips 7 secured to the end portions thereof, each cross strip being provided with depending ears 8 at its ends and which ears project close to the openings 5. 85

Pivots connected to the ears 8 at the rear end of the base strip 6 are levers 9 having arms 10 fixedly attached thereto and projecting upwardly therefrom. These levers project downwardly through the openings 5 and constitute the upper portions of the hind legs of the animal, the lower end of each of the levers 9 being forked as at 11 and rounded downwardly and forwardly. A pivot pin 12 extends transversely through the forks and engages an ear 13 extending upwardly from 100

the lower leg portion 14, said ear working within the forks 11. Short strips 15 are secured to the sides of the lower leg portions 14 and project downwardly therefrom, the lower ends of these strips being pivotally connected at 16 to a block 17 constituting the foot portions of the legs. Backward swinging movement of the leg section 14 relative to the leg section 9 is limited by a strap 19 preferably of elastic which is extended along the front faces of the leg portions 9 and 14 and is attached at its upper end to the leg portion 9 and at its lower end to the leg portion 14. Thus leg portion 14 is free to swing forwardly about the pivot 12 but has a limited backward swinging movement about said pivot.

Each of the hind legs of the animal is constructed as described. Each of the front legs is also constructed in this manner. By referring to the drawing it will be seen that each front leg includes a lever 20 pivotally mounted, as at 21, upon one of the ears 8 and having an arm 22 extending upwardly therefrom. The lower portion 23 of the leg extends into and is pivotally attached to the leg portion 20 as shown at 24 and also has a block 25 connected to the lower end thereof and constitutes a foot portion. A strap 26 similar to the strap 19 is provided for limiting the backward swinging movement of the lower leg portion 23 relative to the upper leg portion 20.

A spring motor of any preferred construction and which has been indicated generally at 26 is fixedly mounted on the adjacent strip 6, there being a winding stem 27 extending therefrom toward an opening 28 in the body portion 1 so that a suitable winding key can thus be placed in engagement with the arbor or stem for the purpose of winding the spring of the motor. The motor includes in its construction the usual fan 29 and this fan normally engages a stop finger 30 extending laterally from a lever 31 which is pivotally mounted, as at 32, upon the frame 33 of the motor. A rod 34 is connected to the free end of the lever 31 and extends upwardly through the top of the body casing 1 where it is provided with a knob 35 or the like by means of which the rod can be raised easily for the purpose of shifting the finger 30 out of the path of the fan 29 and thereby releasing the motor. Lever 31 engages the frame 33 with sufficient friction to cause said lever to remain in any position to which it may be moved by the rod 34.

The motor includes in its construction a large gear 36 to which are attached oppositely extending cranks 37, 38 and 39.

Upstanding from the rear cross strip 7 is a post 40 on which is fulcrumed a transversely extending lever 41. The ends of this lever loosely engage the respective arms 10 of the rear legs and to one of these arms 10

is attached a pitman 42 connected to the crank arm 37. Another post 43 extends upwardly from the front cross strip 7 and a transverse lever 44 is fulcrumed thereon, the ends of this lever being loosely engaged with the arms 22 of the front legs of the toy. To one of these arms 22 is attached a pitman 45 connected to and actuated by the crank arm 38.

Attached to the frame 33 of the motor at that side thereof remote from the crank arms 37, 38 and 39, is a lever 46 connected by a pitman 47 to one of the arms 10 of the rear legs. Extending forwardly from the upper portion of the front of the body 1 is an arm 48 and another arm 49 is extended forwardly from the front cross strip 7. Arranged between the forward ends of these arms and pivotally connected to them as at 50, is the rear portion of the head casing 51 shaped to simulate the head of an animal, the rear portion of this casing 51 being open while the front portion is shaped to provide an upper jaw 52. Openings 53 for the eyes and openings 54 for the ears are also provided within this casing. A bracket 55 is attached to one side of the head casing 51 and this bracket is connected by a pitman 56 to the lever 46.

The crank arm 39 has a downwardly projecting extension 57 connected by a pitman 58 to a finger 59 extending upwardly from one end of a transverse lever 60. This lever extends under the base strip 6 and is provided at the other side of said strip with an upstanding ear 61. Extending rearwardly from and attached to the finger 59 is a cord 62 slidably engaging a guide 63 which is supported by an arm 64 close to but back of one of the hind legs of the toy close to its point of attachment to the ear 8. From this guide 63 the cord is extended downwardly and is attached firmly to the lower leg portion 14 close to and back of its pivot 12, as shown at 65. Another cord 66 is attached to the finger 59 and extends forwardly therefrom over a guide 67 attached to the base strip 6 close to and above the opening 5 through which one of the front leg portions is extended. From this guide 67 the cord is extended downwardly and is fixedly attached, as at 68, to the lower leg portion 23 of one of the front legs of the toy at a point close to but back of the pivot 24. A cord 69 is attached to the ear 61 and is extended forwardly therefrom to a guide 70 corresponding with the guide 67 and likewise attached to the base strip 6. The cord is extended downwardly from this guide and is attached to the lower leg portion 23 of the other front leg of the toy at a point close to and back of the pivot 24, as shown at 71 in Figure 2. Another cord 72 is attached to the ear 61 and is extended rearwardly therefrom to a guide 73 carried by an arm 74 extending through the opening of the other rear leg and

125
130

from this guide the cord is extended downwardly to the lower leg portion 14 of said hind leg to which it is attached close to and back of the pivot 12 as shown at 75.

From the foregoing description it is believed that the operation of the leg portions and the head will be apparent. When the motor is released by lifting the knob 35 the cranks 37, 38 and 39 will be rotated at the desired speed. Crank 37 will operate pitman 42 and cause the lever 41 to oscillate. Thus as one hind leg is swung forwardly through the action of this lever 41 thrusting against one of the arms 10, the other hind leg will be swung rearwardly relative to the body. At the same time motion will be transmitted from the crank arm 38 through pitman 45 to lever 44 where a similar action takes place, the front right leg being swung rearwardly relative to the body portion while the hind right leg is being swung forwardly relative to the body portion. At the same time the left front leg is being swung forwardly while the left hind leg is being swung rearwardly. This movement takes place during one-half the rotation of the crank arms. During the other half of the rotation thereof the movement of the legs will be reversed. At all times during this back and forth movement of the legs, the blocks 17 and 25 will work freely about their pivotal connections so as to adjust themselves automatically to the surface over which the toy is travelling. As the legs are thus being actuated motion is being transmitted to the transverse lever 60 from the crank arm 39, its extension 57 and the pitman 58. When the legs reach the positions shown in Figures 1 and 2 and are about to start movements in reverse direction, lever 60 shifts the several cords connected thereto so as to pull on the lower leg portions of the legs in properly timed succession with the result that when a leg is in its forwardly extended position the cord connected to the lower portion thereof will be pulled taut whereas when the leg is in its rearmost position the cord will be paid out so as to allow the lower leg portion to swing forwardly to a new position. The action of the levers and cords on the leg sections has been illustrated clearly in Figures 6, 7, 8, and 9.

Figure 6 illustrates the leg as it is about to swing forwardly. It will be noted that at this time the cord 66 is slack. While the front left leg and the rear right leg are in the positions shown in Figure 9, at which time the body of the toy is being moved forwardly about the pivotal connections between the leg sections 23 and 25, the front right leg and the rear left leg are brought to the position shown in Figure 7 at which time leg section 20 is swung forwardly, section 23 is pulled upwardly and rearwardly and pressure of the foot section 25 upon the supporting sur-

face is relieved. This movement of leg section 23 to the position shown in Figure 7 necessitates a slight elongation of the elastic strip 26. As the front left leg and the rear right leg reach the rear limits of their movement as shown in Figure 6 the front right leg and the rear left leg are brought to their foremost positions as shown in Figure 8. Then as the front left leg and the rear right leg begin to move forwardly as shown in Figure 7 the front right leg and the rear left leg will start backwardly as shown in Figure 9 picking up the weight of the body and retaining the load until these legs reach the position shown in Figure 6. Thus as a result of the properly timed movements of the parts, the actuation of the motor will result in the toy walking forwardly.

During the operation described lever 46 will operate pitman 56 with the result that the head portion will be swung from side to side.

For the purpose of adding to the realistic appearance of the toy, a lever 76 is fulcrumed in the head portion with one arm extending forwardly under the fixed jaw 52 and enlarged so as to constitute a lower jaw, as shown at 77. A guide rod 78 is extended longitudinally along the upper arm of lever 76 and slidable thereon are the offset portions 79 of a strip 80 simulating a tongue. This tongue is arranged above the jaw 77 and is extended longitudinally thereof. A spring 81 is mounted on the rod 78 and bears at one end against one of the offset portions 77 and at its other end against a stop 82 on the lever 76. Thus the spring serves to hold the tongue normally extended forwardly relative to the jaws. A guide 83, which can be in the form of a pulley, is attached to the upper portion of the head casing 51 and this guide is adapted to support two cords 84 and 85 respectively. The cord 84 is attached to one of the arms 22 and is also attached to the strip 80. The cord 85 is attached to the other arm 22 and to the inner end of the lever 76. Thus it will be seen that as the front legs of the toy are moved back and forth during the operation of the toy, the jaw 77 will be pulled downwardly by the upward pull of cord 75 on the inner end of lever 76 and will be subsequently returned to its normal position by the pulling action of a spring 86 which is attached to lever 76 and to the lower portion of the head casing 51. At the same time cord 84 will pull on the tongue 80 so as to retract it against the action of spring 81 after which said tongue will be released and will be projected forwardly by the spring. Extending across each of the eye openings 53 is a pin 87 journaled for rotation in bearings 88 and carrying an eye 89 of glass or any other suitable material exposed within the opening 53. A finger 90 is extended downwardly from the pin 87 and

is connected by a spring 91 to the front portion of the head casing 51. A cord 92 is extended from this finger 90 to a lever 94 fulcrumed within the head casing 51 close to one of the openings 54. The upper portion of this lever is extended through the opening and constitutes an ear 95. A cord 96 extends from lever 94 to one of the arms 22. It is to be understood that one eye and one ear are thus connected to one of the arms 22 while the other eye and the other ear are connected in the same manner to the other arm 22. Consequently as the toy is moved the eyes will be caused to move and the ears will also work back and forth.

To complete the natural appearance of the toy the entire body and head portion as well as the legs may be covered with fur or any other suitable flexible material indicated generally at 97.

What is claimed is:

1. An animated toy including a body portion, a spring motor therein, articulated legs pivotally connected to and extending from the body portion, each leg including an upper leg portion, a lower leg portion and a foot portion mounted for relative movement, means operated by the motor for simultaneously moving forwardly one front leg and the diagonally opposed rear leg and for moving rearwardly one front leg and the diametrically opposed rear leg, and means controlled by the motor for holding the lower leg portion against swinging movement relative to the upper leg portion during the last portion of its forward movement and the first portion of its rearward movement and for releasing said lower leg portion to swing relative to the upper leg portion during the remaining swinging movement of the legs, said means including an elastic strap connecting the upper leg portion to the lower leg portion at the front thereof, an actuating cord connected to the lower leg portion at the back thereof, and a motor operated lever connected to the cord for holding said cord taut during the latter portion of the forward movement and first portion of the rearward movement of the leg, thereby to stretch the strap of said leg, and for producing slack in the cord during the latter portion of the rearward movement and first portion of the forward movement of the leg.

2. An animated toy including a body portion, articulated leg portions pivotally connected thereto, each leg portion including an upper portion, a lower portion, and a foot portion connected for relative swinging, elastic connections between the upper and lower portions of each leg for limiting the rearward swinging movement of the lower portion relative to the upper portion, cords connected to the back portions of the lower leg portions, a spring motor for swinging the legs relative to the body to cause the diagonal-

ly opposed legs to move simultaneously in the same direction, and means controlled by the motor for alternately pulling and paying out the cords in properly timed relation to the swinging of the legs, thereby to hold the lower leg portions against movement relative to the upper leg portions during the first portion of the rearward swinging movement of the legs and the last portion of the forward swinging movement thereof and to permit free forward swinging of the lower leg portions relative to the upper leg portions during the first portion of the forward movement of the legs, said cords being at all times in direct connection with their actuating means.

3. An animated toy including a body portion, articulated legs pivotally connected thereto, each leg including an upper leg portion, a lower leg portion, and a foot portion pivotally connected, arms extending into the body from the leg portion, a spring motor within the body, driving connections which at all times positively join the motor and the arms for actuating the legs to move diagonally opposed legs in the same direction simultaneously, two of the legs being movable in one direction while the remaining legs are movable in the opposite directions, elastic means for yieldingly holding the lower leg portions against swinging movement relative to the upper leg portions during the backward swinging movement of the legs and motor operated means for releasing the lower leg portions for free forward swinging relative to the upper leg portions during the first portion of the forward swinging of the legs and for pulling upon the lower leg portions during the latter portion of the forward movement thereof.

In testimony that I claim the forgoing as my own, I have hereto affixed my signature.

HERBERT EDWARD PRICE.
